UNITED STATES PATENT OFFICE

2,459,583

COMBUSTION APPARATUS

Gustave C. Peter, Wauwatosa, Wis.

Application June 29, 1944, Serial No. 542,709

4 Claims. (Cl. 251—34)

1

The present invention relates to combustion apparatus of the type that employs liquid fuel vaporizers, having particular reference to a novel type of fuel flow control valve to be used in conjunction therewith, and is a continuation-in-part of my copending application Serial No. 508,490, filed November 1, 1943, now abandoned.

A principal object of the invention is to provide means selectively to vary the amount of air entering the vaporizer, and means cooperatively associated with the air control means relatively to vary the amount of fuel entering the vaporizer.

More specifically, it is an object of the invention to provide a combustion apparatus having means disposed at the top of the vaporizer for changing the size of the opening between the vaporizer and combustion chamber, the means preferably comprising one or more annular disks each having a central opening of smaller size than the opening between the vaporizer and the combustion chamber, thereby selectively to vary the amount of air entering the vaporizer, and a fuel flow control valve connected with disk operating mechanism selectively to vary the amount of fuel entering the vaporizer in accordance with the position of the chosen disk on the vaporizer.

Another object of the invention is to provide a liquid fuel valve for combustion apparatus employing a fuel vaporizer, comprising a valve member having an outlet therein for communication with a fuel conduit, and means for opening and closing the outlet selectively to vary the amount of fuel permitted to flow through the valve between high and low fire operating positions.

Other objects of the invention will in part be obvious and will in part appear hereinafter.

The invention accordingly comprises a device possessing the features, properties, and relation of elements which will be exemplified in the device hereinafter described and the scope of the application of which will be indicated in the claims.

For a fuller understanding of the nature and objects of the invention reference should be had to the following detailed description, taken in connection with the accompanying drawings, in which:

Fig. 1 is an elevational view illustrating a preferred embodiment of liquid fuel flow control valve contemplated by the present invention, mounted in position in a conventional float valve shown fragmentarily and in section, depicting the valve in position for high flow of fuel;

Fig. 2 is a view similar to Fig. 1 depicting the valve arranged in position for intermediate flow;

2

Fig. 3 is another view similar to Figs. 1 and 2 depicting the valve arranged in position for low flow;

Fig. 4 is a vertical sectional view of the lower portion of a combustion apparatus and vaporizer, generally illustrating the position of the valve of Figs. 1 through 3 to be used in conjunction therewith;

Fig. 5 is a plan view of the arrangement shown in Fig. 4, illustrating a preferred form of actuating mechanism between the disk means for regulating the quantity of air drawn into the vaporizer, and the valve for regulating the flow of liquid fuel thereto; and

Fig. 6 is a vertical end elevational view, taken along the line 6—6 of Fig. 5 and looking in the direction of the arrows, partly in section, further illustrating the actuating mechanism between the disk operating means for regulating the air control and the valve device for regulating the fuel control.

The combustion apparatus, or space heater, utilizing the vaporizer, or vaporizing pot, which is herein illustrated is of the type disclosed in the Breese patents, particularly those shown in Patents Nos. 2,179,610 and 2,181,261. These patents disclose various modifications of means for selectively varying the amount of air which is permitted to be drawn into a vaporizer.

The present invention contemplates the use of such devices, as well as others suitable for selectively regulating the quantity of air drawn into the vaporizer, in combination with the liquid fuel control device, or valve, hereinafter more fully described.

Briefly, conventional burners of this type utilize a small amount of hydrocarbon oil passed through a conduit, or fuel pipe, entering the bottom of the vaporizer. This is ignited by any suitable means.

Initially, combustion occurs immediately above the surface of the oil, resulting in considerable smoke and soot. The heat resulting from combustion vaporizes the oil that is fed through the fuel pipe once combustion is started. Thereafter, the place where combustion occurs depends largely upon the rate at which the oil is fed to the burner.

With a restricted flow of oil to the burner, as for low fire operation, combustion occurs in the lower portion of the vaporizer. By increasing the flow of oil there is a corresponding increase in the amount of vapors generated, and the lower limit of the zone of combustion moves upward away from the surface of the oil in the vaporizer.

When the flow of oil is increased to maximum, for

high fire operation, the zone of combustion moves still further away from the surface of the oil, and eventually the lower limit thereof becomes localized in the region known as the combustion chamber, or zone, extending through and above the top of the vaporizer.

Referring more particularly to the drawings, there is indicated generally at 10 a combustion apparatus, or space heater, with a vaporizer, and illustrating a preferred embodiment of means for practicing the principles of the present invention. The apparatus consists of a cylindrical shell 11 surrounded by an outer shell 12. In the lower portion of the shell 12 is secured an annular flange 13. Suspended from this flange is a vaporizer, or vaporizer pot, 14.

The side walls of this vaporizer preferably are perforated, as at 15, and these perforations are known as the primary air inlets. Near the top of the vaporizer is another series of perforations 16 more closely grouped together. These perforations are known as the secondary air inlets.

On top of the pot 14 is a disk 17 having a central opening therein indicated generally at 18. Through this opening, and in the area indicated generally at 19, is the combustion zone, or chamber.

The foregoing apparatus has certain disadvantages. At the high fire stage of operation all, or substantially all, of the air admitted to the vaporizer through the primary air inlets 15, is admixed with the oil vapor, prior to the burning of the vapor. At high fire with a full flow of oil such burners are very efficient. However, with a low supply of oil the amount of air drawn through the vaporizer remains the same as for high fire operation and the mixture of air and vapor becomes combustible before reaching the region of the secondary air inlets 16. In other words, under such conditions, combustion takes place toward the bottom of the vaporizer. This results in inefficient utilization of the fuel, evidenced by a smoky flame and the accumulation of carbon in the burner.

In the patents above referred to, this problem was solved by regulating the flow of air by controlling the size of the opening at the top of the vaporizer. That is to say, when the flow of liquid fuel to the vaporizer diminishes, the size of the aperture at the top of the burner is correspondingly diminished in cross section.

A preferred form of means utilizes one or more annular disks with smaller openings than that already in the conventional disk disposed at the top of the burner. This is done by hingedly affixing such disks to the top of the vaporizer in such a manner that they can be swung into and out of position by means of rods with handles extending exteriorly of the apparatus.

In the accompanying drawing two of such disks have been illustrated in upwardly raised position. One of these disks 20 has a very small opening 21 therein. When such a disk is lowered into position by means of the rod 22, the amount of air which is permitted to pass through the primary air inlets 15, and secondary air inlets 16, is reduced to a minimum. Such disk is used when it is desirable to pass a low amount of air into the vaporizer 14. This then permits low fire operation of the combustion apparatus. When it is desirable to restore the device to high fire operation it is but necessary to swing the disk into upraised position as indicated, and increase the amount of air to maximum. In either case it is necessary independently to regulate

the amount of oil flowing to the vaporizer to accommodate these varying conditions of high and low fire.

When it is desirable to have a medium fire, the intermediate annular disk 23, having a central opening 24, is utilized. This central opening is of intermediate cross sectional area when compared to the opening 18 in the top of the vaporizer and the central opening 21 in the disk 20. The disk 23 is lowered into position over the opening 18 also by means of a rod 22. Each rod, 22 is equipped with a handle 25 at its end. With the disk 23 lowered into position it is again necessary independently to regulate the flow of liquid fuel passing into the vaporizer to an amount to accommodate medium fire conditions.

It would be a distinct advantage to be able properly to regulate and vary the amount of liquid fuel passing into the vaporizer automatically relatively to the amount of air which is drawn through the vaporizer. This is accomplished by means of the present invention.

Referring more particularly to Figs. 1, 2 and 3 of the drawings, there is shown a liquid fuel flow control device, or valve, indicated generally at 26 variously positioned to permit high flow, intermediate flow, and low flow of liquid fuel to obtain high, medium, and low fire respectively, in the burner. The valve will be described in that order of operation.

A preferred embodiment of the valve as herein disclosed includes a valve stem 27 having an opening, or gate, 28 at its lower end for the passage of liquid fuel. The longitudinal opening 28 connects the exterior of the stem 27 with a longitudinal recess of equal or greater extent in the end of the stem. The size of this opening regulates the flow of the fuel. In other words, the opening, or gate, 28 may be a longitudinal groove or slot extending along one side of the stem to its end. It should be noted that this device can be utilized in connection with conventional types of float valves, only a portion of which is shown in the present drawings, as indicated at 29. The outlet for such fuel supply is indicated at 30. The bottom of the valve stem is mounted to rise and descend in the outlet 30. The top of the valve stem is supported by any suitable means, such as brackets 31 securing the device in aligned position to the outer shell 12. The float valve container, or casing, 29, may similarly be attached to the shell 12 in any suitable manner.

In order to regulate and control the size of the opening 28 so as to vary the amount of oil passing therethrough there is provided a movable member, or sleeve, 32, which is slidably mounted over the stem, 27. This sleeve passes outwardly of the container 29 and is provided at its end, preferably with a pulley 33 secured thereto. At the bottom of this pulley is secured a cam follower 34 which is designed to ride upon a cylindrical end cam 35 surrounding the sleeve 32 and secured to the top of the float valve container 29 as indicated at, for example, 36. The sleeve 32 is resiliently mounted by means of a spring 37 surrounding the sleeve and held in tensioned position by a collar 38.

With a valve thus far described, the amount of liquid fuel which is permitted to pass into the vaporizer can nicely be regulated to accommodate either high fire, or low fire operation, as desired. It is of particular advantage that this can be accomplished automatically in combination with a selected amount of air which is permitted to

pass through the vaporizer. The invention especially contemplates the use of such a device in connection with a fire ring such as that indicated at 20 where it is desired to secure very high fire or very low fire without concern as to any intermediate stages of heat required. This arrangement is particularly advantageous for hot water heating systems as well as for central heating plants.

While the particular valve thus far described will be further discussed in connection with the annular disk disposed above the vaporizer, as indicated by the member 20, it should be understood that it is equally adaptable to other forms of means whereby the amount of air which is permitted to pass through the openings in a vaporizer can selectively be varied. For example, such means need not be of the exact shape shown and may be otherwise disposed, for example, immediately over the air inlets. Such air control means can be of any suitable design which will accomplish that purpose, providing the means for operating such a device is cooperatively connected to a valve such as that illustrated by Figs. 1 to 3, so as to operate the same from high to low, or low to high fire.

Any suitable connecting mechanism which will bring about the simultaneous operation of such a valve with such an air control means may be utilized. Such connecting mechanism will now be described, by way of illustration, for use with a single annular disk, or fire ring, of the type shown at 20. Connected to the rod 22 is a pulley 40. Secured around this pulley is a light cable, or wire, 41. The cable passes around an idler pulley 42 suitably secured to the shell 12. The cable then passes around and is secured to the sheave pulley 33.

The operation of the illustrated device can best be understood by reference to Figs. 1 and 3. For example, when the device is set for high fire the cam follower 34 will be raised to its uppermost position on the cam 35 as indicated. Consequently, the sleeve 32 will thereby be drawn into its uppermost position against the tension of the spring 37. This exposes the maximum amount of outlet for the flow of the liquid fuel 43 through the gate 28, outlet 30, and through the pipe 41 leading to the vaporizer 14.

When it is desired to change the operation of the device to low fire, the handle 25 is turned and the shaft 22 and disk 20 moves to horizontal position so that it overlies the flange plate 17. Thus, the amount of air which is permitted to be drawn through the vaporizer can selectively be chosen, for example, from very high, to very low fire. In the meantime the pulley 40 turns the cable, or wire, 41, which in turn rotates the pulley 33 dropping the cam follower 34 to its lowermost position on the cam 35, as indicated in Fig. 3. The sleeve 32 also is lowered under the tension of the spring 37 and covers the opening, or gate, 28 with the exception of a small area permitting a sufficient flow of fuel to operate the burner at low fire. High fire, of course, can again be reached by restoring the disk 20 to vertical position as illustrated in the drawing, also automatically returning the valve 26 to high flow position.

Referring now particularly to Fig. 2, it will be seen that an auxiliary arrangement can be adapted to the valve whereby intermediate fire operation of the burner can be obtained. Here also, it should be understood that the device about to be described is an illustration merely and is

particularly usable with a second ring having an intermediate opening as heretofore described in connection with disk 23. It will become apparent, however, that the same results can be obtained with other modifications, for example, those shown in the above mentioned Breese patents, as well as other types of devices for selectively choosing an intermediate range of fire operation for the burner.

In order to obtain an intermediate flow of liquid fuel for medium fire operation such as, for example, with the disk 23 and intermediate size opening 24, provision has been made to actuate the valve stem 27. This has been accomplished, for example, by resiliently mounting the stem 27 in such a manner that it is actuated to rise and descend in conjunction with the operation of the means for selectively varying the intermediate amount of air permitted to flow into the vaporizer. Here again a cam arrangement can be utilized. A pulley 45 is secured to the stem 27. Above the pulley is a cam follower 46 which rides on end cam 47 secured to under side of the bracket 31. A spring 48, held in position by a collar 49 pinned to the top of the stem 27, maintains the stem 27 in resiliently mounted position.

The operation of the device for medium fire is obtained by an arrangement of pulleys and cable similar to that used in connection with low fire operation. Secured to the other rod 22 is a pulley 50. Passing around this pulley and secured thereto is a cable 51. This cable passes around a pulley 52 also secured to a bracket attached to the shell 12. The cable then passes around the pulley 45, which may also be a sheave pulley, and is secured thereto. When it is desired to bring the parts into operative arrangement for the high fire, especially where two apertured disks, such as 20 and 23, are used, it is first necessary to swing the disk 23 up out of position so that the pulley arrangement connected with that disk places the valve in high fire position, thereby exposing a maximum amount of outlet 28 for the fuel to pass therethrough. When the valve is thus arranged the disk 23 may be swung downwardly over the opening 18 of the vaporizer 14, and the pulley 50 will actuate the pulley 45 by means of the cable 51. The cam follower 46, above the pulley 45, will be drawn to the lowest point of the end cam 47 against the action of the spring 48 on the end of the valve stem 27. This causes the valve stem to plunge into the outlet 30 so that an intermediate portion of the gate 28 is exposed permitting thereby a chosen amount of liquid fuel, 43, to flow through the outlet 30 and through the pipe 41 to the vaporizer 14.

By the foregoing means manual operation of the flow of fuel can be eliminated. In selecting the proper fire by operating the air control means, the oil flow control device is automatically operated, providing a fool-proof arrangement for fuel feed control.

While there has been illustrated a manual operation of means for selectively controlling the amount of air in conjunction with a valve device automatically to vary the amount of fuel in accordance with the air selection, it will of course be apparent that the entire device can be made to operate electrically. However, in such an event it would be more desirable to have a single means for varying the cross sectional dimension of the aperture 18 in the disk 17 rather than the dual arrangement shown.

The mechanical operation of such a device has

many advantages. The proper amount of fuel which is brought into the vaporizer can always be determined automatically without concern by the operator. While float valves, operated electrically, have been used, they are expensive and must be operated from thermostats, an added expense. In connection with the present device, where it is desired to utilize a motor for operating the fire rings, a thermostat may also be utilized, of course, but the operation of the valve does not depend upon the delicate operation of such a thermostat arrangement. It will also be observed that expensive electrical equipment can be eliminated, and that the valve herein illustrated can be used in conjunction with conventional types of float valves and readily adapted thereto. A material saving in initial cost and subsequent operation is effected.

It will thus be seen that the objects hereinbefore set forth can readily and efficiently be attained, and since certain changes may be made in the above device and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent is:

1. A fuel flow control valve adapted to be connected to a float valve container for use with a combustion apparatus of the type that employs a fuel vaporizer having means to regulate the amount of air flowing upwardly therethrough, which comprises a valve member adapted to be mounted in a wall of said container and to extend therethrough to an opposite wall having a fuel outlet therein, said valve member having an opening in one end communicating with said outlet, a flow control member slidably mounted upon said valve member and adapted to extend from within said container through said first named wall and to regulate the area of the opening in said valve member, and means connected to said control member disposed exteriorly of said first named wall to actuate said control member with respect to the opening in said valve member selectively to vary the amount of fuel permitted to flow through said opening to provide high and low fire operation of said apparatus.

2. A fuel flow control valve adapted to be connected to a float valve container for use with a combustion apparatus of the type that employs a fuel vaporizer having means to regulate the amount of air flowing upwardly therethrough, which comprises a valve stem adapted to be mounted in a wall of said container and to extend therethrough to an opposite wall having a fuel outlet therein, said valve stem having an opening in one end communicating with said outlet, a flow control sleeve slidably and resiliently mounted upon said valve stem and adapted to extend through said first named wall to regulate the area of said opening, and means, including a cam member disposed exteriorly of said first named wall and a cam follower therefor connected to said sleeve to actuate said sleeve selectively to vary the amount of fuel permitted to flow through said opening to provide for intermediate and high fire operation of said apparatus.

the opening in said valve stem to provide for high and low fire operation of said apparatus.

3. A fuel flow control valve adapted to be connected to a float valve container for use with a combustion apparatus of the type that employs a fuel vaporizer having means to regulate the amount of air flowing upwardly therethrough, which comprises a valve member adapted to be mounted in a wall of said container and to extend therethrough to an opposite wall having a fuel outlet therein, said valve member having an opening in one end communicating with said outlet, a flow control member mounted upon said valve member and adapted to extend from within said container through said first named wall and to regulate the area of the opening in said valve member, means connected to said control member disposed exteriorly of said first named wall to actuate said control member with respect to the opening in said valve member selectively to vary the amount of fuel permitted to flow through said opening to provide high and low fire operation of said apparatus, and means connected to said valve member and adapted to be disposed exteriorly of said first named wall to actuate said valve member with respect to said fuel outlet and to regulate the area of the opening in said valve member selectively to vary the amount of fuel permitted to flow through said opening to provide for intermediate and high fire operation of said apparatus.

4. A fuel flow control valve adapted to be connected to a float valve container for use with a combustion apparatus of the type that employs a fuel vaporizer having means to regulate the amount of air flowing upwardly therethrough, which comprises a valve stem adapted to be mounted in a wall of said container and to extend therethrough to an opposite wall having a fuel outlet therein, said valve stem having an opening in one end communicating with said outlet, a flow control sleeve slidably and resiliently mounted upon said valve stem and adapted to extend through said first named wall to regulate the area of said opening, means, including a cam member disposed exteriorly of said first named wall and a cam follower therefor connected to said sleeve to actuate said sleeve selectively to vary the amount of fuel permitted to flow through the opening in said valve stem to provide for high and low fire operation of said apparatus, and means, including a cam member adapted to be disposed exteriorly of said first named wall and a cam follower therefor connected to said valve stem to actuate said valve stem with respect to said fuel outlet and to regulate the area of the opening in said valve stem selectively to vary the amount of fuel permitted to flow through said opening to provide for intermediate and high fire operation of said apparatus.
